(57) **CLAIM**

We claim the ornamental design for a “pre-coat filter element,” as shown and described.

DESCRIPTION

FIG. 1 is a top perspective view of the pre-coat filter element according to the present invention;

FIG. 2 is a bottom perspective view of the pre-coat filter element according to the present invention;

FIG. 3 is an elevational left side view of the pre-coat filter element according to the present invention;

FIG. 4 is an elevational right side view of the pre-coat filter element according to the present invention;

FIG. 5 is a bottom view of the pre-coat filter element according to the present invention; and,

FIG. 6 is a top view of the pre-coat filter element according to the present invention.
